Primary Examiner—Jeffrey Asch*Attorney, Agent, or Firm*—Brinks Hofer Gilson & Lione[57] **CLAIM**

The ornamental design for a storage rack, as shown and described.

DESCRIPTION

FIG. 1 is a front right perspective view of a storage rack showing my new design;

FIG. 2 is a right side view thereof;

FIG. 3 is a front view thereof;

FIG. 4 is a rear view thereof;

FIG. 5 is an enlarged sectional view thereof taken along line 5—5 of FIG. 1;

FIG. 6 is a bottom view thereof;

FIG. 7 is a top view thereof; and,

FIG. 8 is a perspective view of a second embodiment of that shown in FIG. 1, the only differences over the first embodiment being encompassed in this single view.

A left side view is symmetrical to the right side shown in FIG. 2.
